CIGARETTE RECEPTABLE AND DISPENSER

Benjamin Olivier, New York, N. Y.

Application June 5, 1946, Serial No. 674,461

3 Claims. (Cl. 312—83)

This invention relates to cigarette dispensers and in particular to a combination receptacle and dispenser.

A particular object of the invention is to construct a cigarette holding and dispensing device that has a large capacity; will keep the cigarettes fresh; will dispense the cigarettes without damage; will discharge cigarettes one at a time at the opposite sides of the device, and one in which the need of mechanical parts is eliminated.

A still further object of the invention is to provide a device of the character referred to which may be made of transparent plastic material such as Lucite so that the cigarettes therein may be displayed and so that the various parts of the device may be made up in different colors to provide an ornamental effect.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a view in perspective of a cigarette dispensing device constructed in accordance with the invention.

Fig. 2 is a view in side elevation of the device illustrated in Fig. 1.

Fig. 3 is a plan view of the device showing the means for mounting the cigarette container therein.

Fig. 4 is a section on the line 4—4 of Fig. 2 showing the device in dispensing operation.

Fig. 5 is a view similar to Fig. 4 showing the ejector in a central non-ejecting position.

Fig. 6 is a section on the line 6—6 of Fig. 4 showing the method of mounting the ejector.

Fig. 7 is a section on the line 7—7 of Fig. 5 further showing the mounting of the ejector.

Fig. 8 is a section on the line 8—8 of Fig. 4 showing the relative positions of the ejector slots in the receptacle and ejector.

Fig. 9 is a view in perspective looking at the bottom of the cigarette receptacle and showing one of the means for mounting the same in the holder.

Fig. 10 is a view in perspective showing a disc used to close one end of the cigarette receptacle.

Fig. 11 is an enlarged fragmentary view in perspective showing the means for slidably mounting the ejector.

Referring to the drawings in detail 10 indicates a holder consisting of a base member 11 of rec-

tangular form preferably bevelled about its edges as at 12 and provided at its opposite side edges with spaced cleats or stops 13. The base has secured thereto, in any suitable manner as by cementing, the vertical side pieces 14, each of which, on the opposing faces, are substantially identical in form and are shaped to provide in the lower portion thereof an arcuate slot 15 opening at the side edges of the members 14 as at 16 to provide a track in which the flanged ends 17 of a semi-cylindrical dispenser 18 is mounted for oscillating movement.

Immediately beneath the ejector, which is slotted as at 19 longitudinally of the center thereof, there is provided an arcuate cradle piece 20 which closely hugs the bottom surface of the dispenser 18 so that a cigarette lodged in the slot 19 will roll along the upper surface of the cradle piece 20 as the dispenser is oscillated in its tracks 20 15.

The cradle piece 20 is connected at its ends to the side or end members 14 and is also suitably secured along the bottom thereof to the base 11. Beneath the side edges of the cradle piece and secured in any suitable manner to the base 11, there are provided guide strips 21 of triangular shape in cross section which provide inclines down which the discharged cigarettes roll to come to rest against the stops 13.

30 The end pieces 14 are each provided centrally thereof with a vertical slot 23 which opens out of the top of the end piece and terminates at its lower end at a point slightly above the track 15 so that a space is left between the cradle piece and 35 the receptacle 24 in which space the dispenser can have free rotative sliding movement. The receptacle consists of a cylindrical container permanently closed at one end by a disc 25 having a rib 26 disposed diametrically thereof and overlying the end of the receptacle body. The opposite end of the receptacle is closed by a similar disc 27 which is frictionally fitted into the end thereof and is held flush by engagement with the edge of the receptacle of projecting portions 28 of

40 a rib 29 which extends diametrically across the disc 27. The receptacle 24 is provided with a slot 30 in the wall thereof and when the receptacle is loaded with cigarettes and the disc 27 is in place, the ribs 26 and 29 will be in alignment with 45 each other and with the slot 30 so that the receptacle can be properly positioned in the holder as illustrated in Figs. 4 and 5.

The ribs 26 and 29 rest in the vertical slots 23 so that the slot 30 of said receptacle opens to the 50 inner or upper surface of the dispenser which, as

shown in Fig. 4, is in the process of transferring one cigarette, which has dropped out of the slot 30 to be lodged in the slot 19 of the dispenser from which it will be discharged, as indicated in outline in Fig. 4, when the slot 19 passes the edge of the cradle piece 20.

The opposite side edges of the ejector 18 are provided with lips 32 constituting finger tabs through the medium of which the dispenser may be oscillated in its track 15 to bring the slot 19 thereof into register with the slot 30 of the receptacle so that cigarettes contained in the latter can drop one at a time from the slot 30 into the slot 19 and be carried along the cradle piece for discharge at either side of the device depending upon the direction of oscillation of the dispenser. When the latter is in the position shown in full lines in Fig. 5 the slots 19 and 30 will be in register and one cigarette will drop into the dispenser. The lips 32 constitute a stop to limit the oscillating movement of the ejector by contact with either of the opposite edges of the cradle member 20. In these positions of the dispenser, the slot 19 has cleared the edges of said cradle strip. When the device is to be loaded, the receptacle 24 is lifted out of the end members 14 and the disc 27 removed so that the receptacle can be refilled.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A combination cigarette receptacle and dispenser comprising a holder including a base and spaced vertical end members each shaped to provide an arcuate track and a vertical groove, a cigarette receptacle removably disposed between the end members in said grooves and having a slot longitudinally of the bottom thereof, a dispenser mounted for oscillating movement in said tracks and having a longitudinal slot for vertical register with the slot of said receptacle, a cradle piece connecting said end members and underlying said dispenser to close the slot in the latter and over the lateral edges of which the slot in the dispenser passes as the latter is oscillated to discharge cigarettes singly at opposite sides of said device, and ribs on the opposite ends of said receptacle for engagement in said vertical grooves

to support the receptacle in place between said end members.

2. A combination cigarette receptacle and dispenser comprising a holder including a base and spaced vertical end members each shaped to provide an arcuate track and a vertical groove, a cigarette receptacle removably disposed between the end members in said grooves and having a slot longitudinally of the bottom thereof, a dispenser mounted for oscillating movement in said tracks and having a longitudinal slot for vertical register with the slot of said receptacle, a cradle piece connecting said end members and underlying said dispenser to close the slot in the latter and over the lateral edges of which the slot in the dispenser passes as the latter is oscillated to discharge cigarettes singly at opposite sides of said device, closure discs in the ends of said receptacle, ribs on said discs overlying the ends of said receptacle and arranged to fit into said vertical grooves, and one of said discs being removably held in the end of said receptacle.

3. A dispensing device comprising a base having end walls mounted thereon, a cylinder disposed horizontally between the end walls and provided with a wall having a longitudinal delivery opening on its lowermost side, a semi-cylindrical dispenser mounted to oscillate under and against said cylinder to close said opening and provided with an opening midway of its sides to receive an article from the opening of the cylinder, said dispenser being provided with stops disposed on opposite sides of the cylinder, a cradle member on which the dispenser may be manually oscillated having a width considerably less than that of the dispenser, and stops located on the base outwardly of the cradle member, whereby the dispenser may be oscillated and delivery may be made on either of the opposite sides of the cylinder.
